UNITED STATES PATENT OFFICE.

WILLIAM A. HOUCK, OF READING, PENNSYLVANIA, ASSIGNOR TO HEMPHILL COMPANY, OF PAWTUCKET, RHODE ISLAND, A CORPORATION OF MASSACHUSETTS.

KNITTED FABRIC.

Application filed August 12, 1919. Serial No. 317,069.

To all whom it may concern:

Be it known that I, WILLIAM A. HOUCK, a citizen of the United States, and a resident of Reading, in the county of Berks and 5 State of Pennsylvania, have invented an Improvement in Knitted Fabrics, of which the following description, in connection with the accompanying drawings, is a specification, like characters on the drawings representing like parts.

10 This invention relates to knitted fabrics. In order that the principle of the invention may be readily understood, I have in the accompanying drawings shown one type of 15 such fabric. In said drawings,—

Fig. 1 is a somewhat diagrammatic representation and upon an enlarged scale of the said fabric produced in accordance with the preferred method of operation herein disclosed and representing the same at one 20 stage of the operation;

Fig. 2 is a similar view but representing the fabric at a different stage of the operation;

25 Fig. 3 represents diagrammatically merely three stages in the formation of the open work or lace work effect;

Fig. 4 represents a portion of the fabric in its complete or final form and shape;

30 Fig. 5 represents a stocking or hose produced by the method herein disclosed;

Fig. 6 represents a portion of knitted fabric formed by the practice of a slight modification of the said method;

35 Fig. 7 is a side elevation of a hose or stocking embodying the fabric shown in Fig. 6;

Fig. 8 indicates diagrammatically certain steps in the production of the fabric 40 shown in Figs. 6 and 7; and

Fig. 9 represents a sinker of special form preferably employed in producing the fabric shown in Figs. 6 and 7.

45 My invention relates more particularly to hosiery or other knitted fabrics with so-called open-work or lace effects caused by structural variations of any suitable character in the knitted fabric. My invention may be practised or carried out by and in many different types of knitting machines, and is in nowise limited in this respect. Preferably, however, I produce the fabric upon a knitting machine of the type disclosed in my Patent No. 1,400,163 and in

accordance with the method fully disclosed in said patent, and to which reference is made for a full disclosure of the method and mechanism for practising my invention.

It has heretofore been proposed to form open or lace-work effects either as longitudinal rows or as zigzag or other lines by a sinker action, but so far as I am aware without satisfactory results. One of the reasons for the failure to secure satisfactory results by a sinker action has been 55 that the yarn or thread with which a special sinker has engaged in a course of loops has in the subsequent and succeeding courses been robbed by the adjacent needle loops with the result that the attempted 60 open or lace work effect has been of irregular and wholly undesirable shape and the adjacent needle portion has been so enlarged 65 that substantially all effect of a predetermined design is lost, the appearance being 70 rather of irregularly shaped loops with 75 improper spacing therebetween.

In the practice of my invention and after a prolonged course of experimentation, I have produced a knitted fabric having open 80 or lace-work effects both as straight longitudinal stripes and as other patterns by causing the special sinkers, shown in my 85 said Patent No. 1,400,163, to engage the yarn or thread during a certain course 90 termed the first course, and upon the next succeeding course causing the throat of such sinker to engage that part of the yarn or thread that was drawn or acted upon by said shoulder in the last preceding course, 95 whereby the yarn or thread which, after 100 said shoulder has acted thereon in the first course, is in part robbed therefrom by the adjacent needle loops in the same course on either side so as unduly and improperly to 105 enlarge said needle loops, is by the throat 27 restored to its former position as the open work, the adjacent needle loops on each side being caused to give up the yarn or thread thus robbed by them. The result 110 is that in the resulting stripe or other pattern of so-called open work or lace effect each edge or margin of the open work or lace effect is well defined and consists of normally and uniformly spaced needle wales. The open or lace effect consists of 115 sinker wales, and the boundary on either side are the needle wales.

I refer to my said patent for a full disclosure and explanation of the method whereby my fabric is made.

Such an open work fabric differs in several particulars from one wherein the open work or lace work stripe or other effects are due to omitted needles or to some other peculiarity of needle action. By the sinker action, as herein described, more yarn is taken than in regular knitting, instead of less where there are omitted needles, the extra amount of yarn being the amount by which the sum of all of the special sinker wales exceeds the sum of the same number of ordinary sinker wales.

In Fig. 1, I have represented with substantial accuracy the shape and condition of the sinker wale or open work stripe produced by the action of one of the special sinkers, such, for example, as the special sinker 18, and of the adjacent needle loops and wales. Viewing said figure, it will be observed that the shoulder 25 thereof engages the yarn at 68 and has produced a bight or loop at such point in the said first course. In the next succeeding course, the throat 27 has engaged the same bight or loop at 68^a and has restored it to its original condition, thus counteracting the robbing to which said loop or bight was subjected by the adjacent needle loop. At 68^b, 68^c and 68^d I have indicated the loop or bight 68,—that is, the open work formation—in the succeeding courses, it being noted that the length of yarn 68^b and 68^d is that of the full open work effect and that the length of yarn 68^b is also of the full open work length, but it is somewhat arched in appearance because the bight or loop has not wholly passed from the sinker.

In Fig. 2, I have represented the appearance of the fabric at the point where the special sinker 18 is fully retracted and is freed from the loop indicated at 68. Such loop is therefore at such point and immediately thereafter robbed or contracted by reason of the enlargement of the adjacent needle loops.

In Fig. 3, I have represented wholly diagrammatically three stages of the operation at A, B, C. At A the special sinker, such as 18, acts upon the yarn to produce the loop or bight 68. Upon the retraction of the sinker, the loop or bight 68 shortens as indicated at 68' and the adjacent needle loops are enlarged as indicated at 69, 70. At C, I have indicated the condition when the throat 27 engages the loop or bight 68 in the second course, the bight or open work effect being indicated at 68', the adjacent needle loops being restored to their normal size as indicated at 69', 70'.

In Fig. 4, I have represented a portion of knitted fabric having an open work stripe 77 therein formed in accordance with the

method herein disclosed. In Fig. 5, I have represented a hose or stocking herein shown as having a ribbed top 71, a leg 72, a high splice 73 above the heel 74 and a toe 75 preceding which is a portion 76 knitted from the toe yarn but by circular knitting. I have herein represented the said hose or stocking as having open work or lace work stripes 77 at the front of the stocking and open work stripes or lace work stripes 78 at the back of the stocking and extending down to the high splice 73. A highly desirable characteristic of my invention is the readiness with which the open work or lace work stripes or other variations or pattern effects based thereon may be provided throughout the entire extent of the stocking both at front and rear and with equal effectiveness.

The ribbed top 71 is incorporated with a section 79 of plain knitting, that is, of knitting formed upon a single set of needles, and it will be observed that in the practice of my invention the open or lace work may be commenced at any point in the stocking and desirably at about the point 80, namely, at the bottom of said section 79 of plain knitting. So far as I am aware, this effect has not heretofore been produced by needle action, neither has it been produced by sinker action prior to my invention.

I have in describing my invention stated that the special sinkers in the first course draw or measure an amount of yarn which is the full amount, but is robbed partially or wholly and is restored in the second course, so that in the completed fabric all the courses from the first show the open work as of the full width. This is a characteristic of my invention, but in Figs. 4 and 5, I have indicated at 81 the open or lace work as having upper tapered ends and at 82 I have indicated the said open work stripes as having tapered lower ends. This desirable and characteristic feature is caused, though it need not be employed, by reason of the fact that the courses of the section of fabric 79 are knitted under full tension and they draw upon the first few courses of the leg part 72 of the stocking wherein the open work stripes appear, with the result that the first few courses of the open work stripe may be of gradually increasing width commencing at substantially zero at the point 83 in Fig. 4 and extending to the point 84, where they are of the full width. This feature of the invention may or may not be employed, but is desirably used. Any suitable fashioning mechanism may be employed, as, for example, fashioning mechanism shown in any patent disclosing the well-known Banner machine, such as the Hemphill Patent No. 933,443, dated September 7, 1909.

In Fig. 6, I have represented a portion of knitted fabric made by cooperating

sinker action in accordance with the somewhat modified form of my invention, and in Fig. 7 I have represented a hose or stocking embodying such knitted structure. In 5 producing the open work effect shown in Figs. 6 and 7, I preferably employ a special form of sinker shown in Fig. 9, and which does not have the characteristic shoulder of that form of sinker shown in the 10 constructions heretofore described. Instead the said sinker herein indicated at 85 is provided with a special throat 86 which engages the yarn at a sinker wale in a first course and in several immediately succeeding 15 courses, such as three or four in number. The action is indicated diagrammatically in Fig. 8, wherein at A' I have indicated the first course and have represented the throat 20 of the sinker 85 as engaging the yarn at 87 so as to produce a sinker wale, which, however, is not of abnormal size as compared with a usual sinker wale, that is, in the completed fabric. In the said first 25 course, the yarn is engaged at 87 by the special sinker and adjacent thereto at each side are the needle wales or loops 88, 89. Upon the second course as diagrammatically indicated at B', another sinker wale is engaged by the throat 86 as indicated at 87^a, 30 the preceding sinker wale 87 being again engaged by the same throat. At C', I have indicated the appearance of the completed fabric and therein have indicated the sinker wales 87, 87'. It will be observed that the 35 said sinker wales are of normal size. I have indicated the needle wales adjacent thereto on either side at 88, 89, and it will be observed that these needle wales are of abnormal size, and in fact of such size 40 as to produce an open work effect as clearly indicated in stripes in Fig. 7. This characteristic two-needle effect, as it may be termed, is produced wholly by sinker action, but the sinker wales themselves are 45 not enlarged, the enlargement being wholly in the adjoining needle wales on each side. This enlargement is due evidently or apparently to the fact that the two needles upon which the loops 88, 89 are formed are 50 at or substantially at the lowest knitting point at this time and therefore draw a slightly additional amount of yarn from the supply. This additional amount thus appears in the needle loops or wales and not 55 in the sinker wales.

In the hose or stocking shown in Figs. 6 and 7, the open work stripes are provided with tapered ends of the same character as those indicated in Figs. 4 and 5.

60 I do not in this application claim the mechanism herein disclosed, as the same is disclosed in and claimed in my co-pending application, Serial No. 317,078, filed August 12, 1919.

65 Having thus described the said fabric,

I desire it to be understood that although specific terms are employed, they are used in a generic and descriptive sense and not for purposes of limitation, the scope of the invention being set forth in the following 70 claims.

Claims—

1. A plain knitted fabric composed of alternating needle wales and sinker wales, 75 said needle wales being of uniform size and shape throughout the fabric and the needle loops of all the needle wales being of uniform size and shape throughout the fabric, a plurality of said sinker wales each severally presenting prolonged open-work formation parallel with and wholly between two next adjacent needle wales, and each such prolonged open-work sinker wale formation consisting of a multiplicity of sinker loops in immediately successive courses, all said 80 sinker loops being of substantially the same length, and each said sinker loop composed of all the yarn originally apportioned thereto and which is markedly in excess of the normal sinker loops of the fabric, each 85 of said sinker open-work wales having throughout sharply defined parallel edges and the two needle wales immediately bounding each said open-work formation sinker wale on each side of such sinker wale 90 being composed wholly of needle loops all of the same size and shape as the normal needle loops elsewhere throughout the 95 fabric.

2. A plain knitted fabric composed of alternating needle wales and normal sinker wales and interspersed abnormal sinker wales, said needle wales being of uniform size and shape throughout the fabric and the needle loops of all the needle wales being of uniform size and shape throughout the fabric, said abnormal sinker wales each presenting prolonged open-work formation parallel with and wholly between two next adjacent needle wales, and each such prolonged open-work sinker wale formation consisting of a multiplicity of sinker loops in immediately successive courses, all said sinker loops being unrobbed and of substantially 100 the same size and length and markedly larger than the normal sinker loops of the fabric, each of said abnormal sinker wales having sharply defined parallel edges and the two needle wales immediately bounding each said open-work formation or abnormal 105 sinker wale on each side of such abnormal sinker wale being composed wholly of needle loops all of the same size and shape as the normal needle loops elsewhere throughout the 110 fabric.

3. A circular knitted hose or stocking consisting of plain fabric made up of alternating needle wales and sinker wales, said needle wales being of uniform size and shape 115 throughout the fabric and the needle loops 120 throughout the fabric and the needle loops 125 throughout the fabric and the needle loops 130

of all the needle wales being of uniform size and shape throughout the fabric, and a majority of said sinker wales being of normal size and shape but having interspersed 5 thereamong a plurality of abnormally large sinker wales, each said abnormally large sinker wale presenting prolonged open-work formation parallel with and wholly between two next adjacent needle wales and 10 each such prolonged open-work sinker wale formation consisting of a multiplicity of sinker loops in immediately successive courses, all of said abnormally large sinker loops being of substantially the same length 15 and each said sinker loop being unrobbed and of a size markedly in excess of the normal sinker loop of the fabric, each of said sinker open-work wales having throughout sharply defined, parallel edges and the two 20 needle wales immediately bounding each said open-work formation sinker wale on each side of such open-work sinker wale being composed wholly of needle loops all of the same size and shape as the normal needle 25 loops elsewhere throughout the fabric, said abnormally enlarged sinker wales being located both at the front and at the back of the hose or stocking and extending into the top of the foot thereof but not into the high 30 splice or sole of the foot.

4. A plain knitted fabric composed of al-

ternating needle wales and normal sinker wales and interspersed abnormal sinker wales, said needle wales being of uniform size and shape throughout the fabric, and 35 the needle loops of all the needle wales being of uniform size and shape throughout the fabric, said abnormal sinker wales each presenting prolonged open-work formation parallel with and wholly between two next 40 adjacent needle wales, and each such prolonged open-work sinker wale formation consisting of a multiplicity of sinker loops in immediately successive courses, all of said sinker loops being unrobbed by the adjoining needle loops on each side, all said sinker loops being of substantially the same size 45 and length throughout the open-work sinker wale formation and markedly larger than the normal sinker loops of the fabric, each 50 of said abnormal sinker wales having sharply defined parallel edges throughout their extent and the two needle wales immediately bounding each said open-work formation or abnormal sinker wale on each side 55 of such abnormal sinker wale being composed wholly of needle loops, all of the same size and shape as the normal needle loops elsewhere throughout the fabric.

In testimony whereof, I have signed my 60 name to this specification.

WILLIAM A. HOUCK.
